UNITED STATES PATENT OFFICE.

FRANKLIN H. WAITE, OF MANKATO, MINNESOTA.

MATCH-SAFE.

SPECIFICATION forming part of Letters Patent No. 289,190, dated November 27, 1883.

Application filed March 5, 1883. (No model.)

To all whom it may concern:

Be it known that I, FRANKLIN H. WAITE, a citizen of the United States, residing at Mankato, in the county of Blue Earth and State of Minnesota, have invented a new and useful Improvement in Match-Safes, of which the following is a specification.

My invention renders the match-safe air-tight, and I attain the object by the mechanism illustrated in accompanying drawings, in which—

Figure 1 is a perspective view of the safe. Fig. 2 is a transverse section, showing the lid partly open. Fig. 3 is a plan of the top edge 15 of the safe before it is attached thereto, as it appears without the flange E. Fig. 4 is an enlarged section, also showing the construction of the top edge of the safe, and exhibits the flange E.

E is a flange projecting outwardly from the top edge of the safe, upon which is laid a flat strip 20 of india-rubber, B, and over the outer edge of said E and B is folded a metal clamp, A, which is intended to secure a part of the india-rubber 25 tight to the safe by means of rivets driven through it and through E and B. About one-third of an inch in width of B lies flat and unfastened on the flange E, and on the inner side

of the safe, and so much of it is uncovered by the clamp A. Upon the uncovered part 30 of B falls the lid D, which is made heavy, in order to press so hard on the india-rubber as to make the safe air-tight on the top. The door D cannot open to a perpendicular line before it hits the upper back of the safe, which projects inwardly, and therefore shuts by its own weight. The fastening of A, B, and E on the outer edge is so tight as to exclude air from that edge of the safe. The flange E is covered by the india-rubber B and by the clamp A, so 35 as to be invisible.

What I claim, and desire to secure by Letters Patent of the United States, is—

The combination of the flange E, surrounding the top of the safe, the rubber bed B, extending around the top of the safe and resting on the flange E, the clamp A, by which the flange and rubber are held firmly together, and the lid provided with the extension D, substantially as and for the purpose set forth. 45 50

Dated at the city of Mankato, Minnesota, February 26, 1883.

FRANKLIN H. WAITE.
